FURNITURE PULL

William Doyle Watt, Jr., Grand Rapids, Mich., assignor to Keeler Brass Company, Grand Rapids, Mich.

Filed Apr. 23, 1971, Ser. No. 137,103

Term of patent 14 years

Int. Cl. D8—06
U.S. Cl. D8—158

FIG. 1

FIG. 2

FIG. 4

FIG. 1 is a perspective view of the furniture pull embodying my new design;

FIG. 2 is a plan view of the furniture pull seen in FIG. 1;

FIG. 3 is a sectional view taken along line III—III of FIG. 1; and

FIG. 4 is a side elevational view of the furniture pull shown in FIGS. 1 and 2.

I claim:

The ornamental design for a furniture pull, substantially as shown.
